J. R. MURPHY.

WHEEL PULLER.

APPLICATION FILED AUG. 26, 1914.

Patented July 20, 1915.

UNITED STATES PATENT OFFICE.

JOHN R. MURPHY, OF CARNEGIE, OKLAHOMA.

WHEEL-PULLER.

1,146,897.

Specification of Letters Patent.

Patented July 20, 1915.

Application filed August 26, 1914. Serial No. 853,774.

To all whom it may concern:

Be it known that I, JOHN R. MURPHY, a citizen of the United States, residing at Carnegie, in the county of Caddo and State of Oklahoma, have invented new and useful Improvements in Wheel-Pullers, of which the following is a specification.

This invention relates to wheel pullers, the object in view being to produce a simple and effective device of the class described having convenient and reliable operating means whereby a gradual and powerful pull may be had on a wheel which is mounted fast on a shaft and cannot well be removed by hand, 10 the operating device enabling a step by step movement to be imparted to the jack screw which operates against the end of the shaft from which the wheel is to be removed.

With the above and other objects in view, 20 the invention consists in the novel construction, combination and arrangement of parts, as herein described, illustrated and claimed.

In the accompanying drawings:—Figure 1 is a plan view of the wheel puller of this 25 invention. Fig. 2 is a longitudinal section showing the screw in elevation. Fig. 3 is a fragmentary perspective view of one end of the screw. Fig. 4 is an end elevation of the whole device showing the operating lever 30 in side elevation. Fig. 5 is a detail perspective view of the forked pawl.

The wheel puller contemplated in this invention comprises a cross head 1 and a pair of wheel engaging hooks 2 which are preferably forked or slotted to receive the opposite 35 ends of the cross head 1 to which the hooks are preferably connected by means of pins 3 to enable the hooks to be moved into and out of engagement with the rim of the wheel to 40 be removed from a shaft. The cross head 1 is centrally enlarged as shown at 4 and internally threaded to receive a jack screw 5 the shaft engaging end of which is preferably rounded as indicated at 6 so as to bear 45 against the end of a shaft. The opposite end portion of the screw 5 is squared in cross section and made tapering as shown, thereby forming a squared and tapering shoulder 7 which fits into the correspondingly shaped 50 central opening 8 of a wheel 9, the latter being provided on its periphery with ratchet teeth 10 and on its opposite side faces with teeth 11 the purpose of which will presently appear. At opposite sides of the square and 55 tapering seat 7, the shaft is provided with journal portions 12 round in cross section

to receive and admit of the turning and sliding movement thereon of the arms 12' of an operating lever 13, the arms 12' being formed with longitudinal slots 14 to receive the tapered end of the screw. In forming 60 the reduced journals 12, shoulders α and β are provided at opposite sides of said journal for the purpose of confining or holding in position the arms 12' of the lever 13 and thereby also holding the wheel 9 in proper 65 position upon and in relation to the tapered and squared shank of the screw, when the device is in actual operation. When the device is not in use, the construction hereinabove described enables the lever 13 and the wheel 9 to be removed from the squared and tapered portion of the screw 5 so that the several parts of the complete tool may be compactly stored or shipped. Pivottally 70 connected to one side of the lever is a pawl 15 the point of which is adapted to engage the ratchet teeth 10 of the wheel 9. Pivottally connected to and working on the opposite side of the lever 13 is a pawl 16 75 having a forked or slotted extremity 17 which straddles the wheel 9 and engages the escapement teeth 11 thereof.

In operation, the hooks 2 are engaged with the rim of the wheel to be removed from its 80 shaft and the rounded extremity 6 of the jack screw is engaged with the end of the shaft. The lever 13 is then moved back and forth, the ratchet teeth 10 being engaged by the pawl 15. In this way a gradual step by 85 90 movement is imparted to the jack screw until the wheel is loosened from its position on the shaft. When not required for immediate use, the operating lever and the wheel 9 may be slid off the tapered and squared 95 end portion of the jack screw and the hooks 2 and jack screw may be disconnected from the cross head 1 thus enabling the device to be compactly stored away for future use. The pawl 16 co-operates with the teeth 11 to 100 back the jack screw and loosen the wheel puller so that it may be removed from the wheel.

The slots 14 are of such length and width as to permit the arms of the lever to be 105 passed over the squared and tapered end portion of the jack screw and to be removed therefrom. In assembling the parts, the ratchet wheel is first placed between the forked arms of the lever and then both the 110 wheel and lever are slid upon the squared and tapered end portion of the jack screw.

until the fork arms are in line with the journals 12. The lever is then moved transversely with relation to the end portion of the jack screw until said arms enter the spaces between the shoulders x and y . This enables the lever to be rocked back and forth without becoming disengaged from the jack screw.

What I claim is:—

- 10 In a wheel puller, the combination of a cross head, wheel engaging hooks mounted thereon, a jack screw threaded through the center of said cross head and embodying a tapering end portion square in cross section, 15 round journals at opposite ends of said squared portion, and shoulders at opposite ends of said squared portions, a wheel having a tapered fit on said squared portion and

provided with ratchet teeth on its periphery and other teeth at opposite sides thereof, a 20 forked lever the arms of which straddle said wheel and are formed with longitudinal slots adapting them to slide transversely of the screw upon the journals thereof and into and out of engagement with said shoulders, 25 a pawl on said lever which engages said ratchet teeth, and a pawl on said lever which has a forked extremity to straddle said wheel and engage said other teeth.

In testimony whereof I affix my signature 30 in presence of two witnesses.

JOHN R. MURPHY.
